US00D517893S

(12) **United States Design Patent** (10) **Patent No.:** **US D517,893 S**
(45) **Date of Patent:** **** Mar. 28, 2006**

(54) **UTILITY KNIFE**

(75) Inventor: **Qui Jian Ping**, Hangzhou (CN)

(73) Assignee: **Great Neck Saw Manufacturers, Inc.**,
Mineola, NY (US)

(**) Term: **14 Years**

(21) Appl. No.: **29/206,221**

(22) Filed: **May 27, 2004**

Related U.S. Application Data

(63) Continuation of application No. 29/181,557, filed on May 13, 2003, now Pat. No. Des. 495,939.

(51) **LOC (8) Cl.** **08-03**

(52) **U.S. Cl.** **D8/99**

(58) **Field of Classification Search** D8/98,
D8/99, 105, 107; 30/154, 155, 156, 158,
30/157, 159, 160, 161, 162, 330, 329

See application file for complete search history.

(74) *Attorney, Agent, or Firm*—Joseph J. Previto

(57) **CLAIM**

The ornamental design for a utility knife, as shown and described.

DESCRIPTION

FIG. 1 is a perspective view of my new design showing it in an unfolded position.

FIG. 2 is a top view thereof.

FIG. 3 is a side view thereof.

FIG. 4 is a front view thereof.

FIG. 5 is a rear view thereof.

FIG. 6 is a bottom view thereof.

FIG. 7 is another side view thereof.

FIG. 8 is a side view thereof showing it in a partially folded position.

FIG. 9 is a side view thereof showing it in a folded position.

FIG. 10 is a perspective view of another embodiment of my new design showing it in an unfolded position.

FIG. 11 is a top view thereof.

FIG. 12 is a side view thereof.

FIG. 13 is a front view thereof.

FIG. 14 is a rear view thereof.

FIG. 15 is a bottom view thereof.

FIG. 16 is another side view thereof.

FIG. 17 is a side view thereof showing it in a partially folded position; and,

FIG. 18 is a side view thereof showing it in a folded position. The broken lines are for illustrative purposes only and form no part of the claimed design.
